UNITED STATES PATENT OFFICE.

THOMAS S. ROUSE, OF BRAZIL, INDIANA, ASSIGNOR TO HYDRAULIC-PRESS BRICK COMPANY, OF ST. LOUIS, MISSOURI, A CORPORATION OF MISSOURI.

BRICKMAKING-MACHINE.

1,168,567.

Specification of Letters Patent. Patented Jan. 18, 1916.

Application filed September 13, 1915. Serial No. 50,432.

To all whom it may concern:

Be it known that I, THOMAS S. ROUSE, a citizen of the United States, residing at Brazil, in the county of Clay and State of 5 Indiana, have invented certain new and useful Improvements in Brickmaking-Machines, of which the following is a specification.

This invention relates to brick making 10 machines and more particularly to a machine or mechanism adapted to ornament or mark in a peculiar manner one or more of the exterior surfaces of a brick, whereby when the brick is assembled with others in 15 a building the entire mass will produce a certain desired effect.

One of the objects of the present invention is to provide a simple and practical mechanism of the above general character 20 which will be inexpensive to manufacture, install and operate.

A further object is to provide a mechanism of the above character which will be reliable and efficient in use and operation.

25 A further object is to provide a mechanism of the above-mentioned character adapted to treat or operate upon one of the surfaces of a clay stream during the manufacture of ornamental brick.

30 Other objects will be in part obvious from the annexed drawings and in part indicated in connection therewith by the following analysis of this invention.

This invention accordingly consists in the 35 features of construction, combination of parts and in the unique relations of the members and in the relative proportioning and disposition thereof, all as more completely outlined herein.

40 To enable others skilled in the art so fully to comprehend the underlying features thereof that they may embody the same by the numerous modifications in structure and relation contemplated by this invention, 45 drawings depicting a preferred form have been annexed as a part of this disclosure, and in such drawings, like characters of reference denote corresponding parts throughout all the views, in which—

50 Figure 1 is an end elevational view of the complete device in operative position showing the manner in which it is adapted to operate upon the clay stream passing therethrough; Fig. 2 is a plan view of the same

mechanism, and Fig. 3 is an elevational view 55 taken at right angles to Fig. 1.

Referring now to the drawings in detail, a table 1 is supported over the clay stream or column indicated at 2 by means of stud bolts 3, which serve as distance pieces between the table 1 and cross bars 4 above which the clay stream is adapted to pass. The upper ends of these bolts 3 are furnished with lock nuts 5 engaging the upper and lower surfaces of the table, thus forming an 60 adjusting mechanism for changing the relative height of the table with respect to the cross bars and the top or upper surface of the clay stream passing therethrough. Upon the table 1 and immediately above the clay 65 stream, as indicated in Fig. 1 of the drawings, there is mounted two upwardly projecting bosses 6, preferably formed integrally with the table and located vertically above the clay stream and in tandem with 70 respect to its direction of motion. These bosses are bored out centrally and are adapted to act as guides for reciprocating plungers 7 provided at their lower ends with plates 8, lying in the same plane as the table 75 1 and above the top of the clay stream. Guide pins 9 project upwardly from the plate 8 through suitable openings in the table 1, and move vertically as the plunger is reciprocated, thus preventing relative 80 rotary movement of the plate 8 and associated parts. Immediately below this plate 8 and in contact therewith is a substantial wooden platen 10 of sufficient size to completely 85 cover the width of the clay stream and have 90 its sides and lower surfaces covered with fleece or the like, as indicated, adapted to contact with the upper surface of the clay stream on depression of the plunger. Into the upper end of the push rod or plunger 7 95 is secured, as by means of a threaded connection, a push rod 11, having suitable adjustable lock nuts 12 at its upper end and a spring 13 adapted to be compressed between washers 14 and 15 engaging the lock nuts 12 100 and boss 6 respectively. These lock nuts 12 serve as a means for compressing the spring 13 about the push rod 11, and thereby determine the force with which the plunger 7 and associated parts return when depressed. 105 These reciprocating plungers may be operated in any desired manner, but the mechanism hereinafter described is believed to

possess certain desirable advantages. A cam shaft 16 is supported in bearings 17 near its ends, which in turn are supported by the cam shaft brackets 18 securely bolted or otherwise secured to the top of the table 1, and preferably occupies a position parallel and above the clay stream. Upon this cam shaft 16 and spaced apart a distance substantially equal to that between the centers of the bosses 6 on plate 1 are securely mounted two cams 19 of similar design, having their throws diametrically opposite one another. Cam shaft 16 is held in position longitudinally by two collars 20 attached theron and immediately outside of the cam shaft bearings 17. A pulley 21 is secured to one end of the shaft, beyond one of the set collars 20, adapted to receive power from any convenient source and transmit the same in a manner to rotate the shaft 16 and cam 17 associated therewith.

Parallel to the cam shaft 17 is a tappet shaft 22 supported in the middle in a suitable bearing 23 firmly bolted or otherwise secured to the top of the table 1 between the cam shaft brackets 18 and bosses 6. This tappet shaft 12 is normally held stationary in its bearings with a clamp fit and tappet arms 24 located on each side of the bearing 23 are allowed to rotate freely thereon but constrained from lateral movement by set collars 25 at each end. As the tappet arms 24 oscillate on the shaft 22 and being similarly disposed thereon, as are the cams 19 on shaft 16, extend backward and directly over these cams 19 whereby they are oscillated at each rotation of the cam shaft. The tappet arms 24 also extend upwardly and directly over the push rods 11. At their ends are preferably provided adjustable set screws having lock nuts 26 which depress rods 11 in their downward movement, the set screws 26 serving as a means of relative adjustment between the rod 11, tappet arms 24 and cam 19.

Having described the construction the operation thereof may be stated as follows: The shaft 16 being driven from the pulley 21 rotates at a desired rate of speed and causes one of the cams 19 to raise under one end of its tappet arms 24, thus depressing the set screw 26 at the other end and causing the push rod 11 and covered platens 10 all to be similarly depressed. As the fabric comes in contact with the top of the clay column it presses back onto the column in a heterogeneous mass the small cuttings and particles which have previously been made and distributed over the bar. The throw of the cams 19 and the relative location of the tappet shaft 22 with respect to the push rod 11 and cam shaft 16 are so proportioned as to give the plunger 7 the necessary vertical thrust. The throw of the two cams 19 being opposite the two plungers 7 are alternately

depressed and raised by the turn spring, and at such a rapid speed relative to the slow moving clay stream that the cuttings are evenly pressed onto the clay bar without impeding its movement over the associated 70 measuring table.

It is thus seen that the present invention provides a simple and practical mechanism for ornamenting and finishing clay streams in the manufacture of brick and one particularly adapted to accomplish among others all of the objects and advantages above set forth. 75

Without further analysis, the foregoing will so fully reveal the gist of this invention that others can by applying current knowledge readily adapt it for various applications without omitting certain features that, from the standpoint of the prior art, fairly constitute essential characteristics of 85 the generic or specific aspects of this invention, and therefore such adaptations should and are intended to be comprehended within the meaning and range of equivalency of the following claims: 90

Having thus described my invention what I claim as new and desire to secure by Letters Patent is:

1. In a machine of the character described, in combination, a support over which a relatively slow moving clay stream is adapted to pass continuously, a second support adjacent said first mentioned support, a reciprocating plunger carried by said second mentioned support having a 95 platen face substantially equal to the face of the clay stream with which it is adapted to co-act, and means for causing a relatively rapid reciprocation of the platen toward and from the face of the clay stream comprising a rapidly rotating shaft and intermediate mechanism between the shaft and the plunger to actuate the latter. 100

2. In a machine of the character described, in combination, a support over which a relatively slow moving clay stream is adapted to pass, a table above said support, a plurality of reciprocating plungers mounted on said table, means for yieldingly holding said plungers in raised position with their effective surfaces out of contact with the clay stream, means for alternately depressing said plungers at a relatively rapid speed, and means for adjusting the throw of the plungers and the force with which their effective surfaces coact with the clay stream. 110

3. In a machine of the character described, in combination, a support over which a relatively slow moving clay stream is adapted to pass, a table above said support, a plurality of reciprocating plungers mounted on said table, means for yieldingly holding said plungers in raised position with their effective surfaces out of contact with the clay stream, means for alternately depressing 115

said plungers at a relatively rapid speed, and means for adjusting the throw of the plungers and the force with which their effective surfaces coact with the clay stream, said 5 means comprising an adjustment permitting a relative movement of the table carrying the plungers toward and from the clay stream.

4. In a machine of the character described, 10 in combination, a support over which a relatively slow continuously moving clay stream is adapted to pass, a table adjacent said support, a plurality of plungers carried by the table having platens at their effective ends 15 substantially equal to the width of the clay stream, a rapidly revolving shaft adjacent the table and intervening means between the shaft and the plungers adapted to rapidly depress said plungers to cause the platens to 20 have a tapping engagement with the surface of the clay stream, and spring means adapted to return the platens to normal position after each depression.

5. In a machine of the character described, 25 in combination, a support over which a relatively slow continuously moving clay stream is adapted to pass, a table adjacent said support, a plurality of plungers carried by the table having platens at their effective ends 30 substantially equal to the width of the clay

stream, a rapidly revolving shaft adjacent the table and intervening means between the shaft and the plungers adapted to rapidly depress said plungers to cause the platens to have a tapping engagement with the surface 35 of the clay stream, and means associated with the platen and table adapted to prevent relative rotation of the platen with respect to the clay stream.

6. In a machine of the character described, 40 in combination, a support on which a clay stream is adapted to pass, a table above said clay stream, a reciprocating plunger mounted upon the table adapted to coact with the clay stream, means for reciprocating said plunger, and means for adjusting the distance between the table and the support for the clay stream, said means comprising a plurality of threaded bolts for said table having lock nuts associated therewith for maintaining the height of the table 45 in predetermined relation to said clay stream.

In testimony whereof I affix my signature in presence of two witnesses.

THOMAS S. ROUSE.
